UNITED STATES PATENT OFFICE.

CHARLES RALPH TOWNSEND, OF BIRMINGHAM, ENGLAND.

ENDLESS-BAND GRINDING AND POLISHING MACHINE.

1,308,610.

Specification of Letters Patent.

Patented July 1, 1919.

Application filed May 7, 1917. Serial No. 166,984.

To all whom it may concern:

Be it known that I, CHARLES RALPH TOWNSEND, subject of the King of Great Britain, residing at Caxton House, Great 5 Charles street, Birmingham, England, engineer, have invented certain new and useful Improvements in Endless-Band Grinding and Polishing Machines, of which the following is a specification.

10 This invention relates to grinding and polishing machines of that type in which an endless band, having its outer surfaces formed or provided with grinding material, runs over two pulleys, one adjacent to each 15 end of a rigid table, and one stretch of said band travels across such table. The chief object of the invention is to provide means to automatically separate the two pulleys over which the endless belt runs in a straight 20 line, which means is always in action whether the pulley shafts are parallel or slightly inclined one to the other without bringing the endless band into contact with the table.

25 The invention is represented by the accompanying drawings applied to a machine having a vertically disposed table.

Figure 1 is a side elevation.

Fig. 2 is an end section.

30 Fig. 3 is a longitudinal sectional detail of the means for slightly inclining the axis of the movable pulley, and

Fig. 4 is a front elevation with the work support removed.

35 The frame of the machine comprises the base a and the elevated part a^2 to which latter at a^3 is detachably and transversely adjustably secured the table c over which the one stretch of the endless band d runs from 40 lower and upper pulleys f and g . The lower pulley f has stationary bearings at a^4 a^5 within the frame. The endless band d is indicated by a dotted line in Fig. 1 and Fig. 2 only, same not being in position in Fig. 4.

45 The upper pulley g has bearings one each side said pulley within brackets g^2 g^3 carried by tubes h and i disposed one each side the table c to slide in lug extensions h^2 h^3 and i^2 i^3 of the machine's frame part a^2 , such

50 straight line sliding movements being parallel with each other and with the surface of the table. Said tubes are jointedly connected at h^4 and i^4 with the brackets g^2 g^3 . By sliding the tubes h and i together within the 55 lug extensions the pulleys f and g may be

separated farther, to thereby put the necessary stretch and tension upon the endless band d .

This stretching and tensioning is automatically arranged for from the operation 60 of the weight x . Collars j and m are oppositely fixed one on each tube, and are, by pivoted links j^2 m^2 , connected with swinging arms n and o of a transverse rocking shaft s having bearings within the machine's frame, 65 a^2 , and to which is connected a long arm x^2 carrying the weight x , whose position can be adjusted along said arm and then fixed by suitable means such as a set screw x^3 . The weight normally operates on the rocking 70 shaft, and, through the short arms, links, and collars, exerts a parallel and even sliding action upon the two tubes h and i , carrying the bearings of the pulley g from the machine's frame, in such manner that the 75 machine has a large amount of movement separating the two pulleys f and g to accommodate a larger range in the different sizes of endless bands, and to automatically tension any of such bands up to its full life, 80 and without any other device except the two pulleys f and g , and the surface of the table c , making physical contact with the endless band.

To slightly incline the axis of the movable 85 pulley g the collar m is provided with a screw-threaded bore m^3 to receive an externally screw-threaded sleeve t revolvably fitted over the tube i between two additional collars u and v fast on the tube. This sleeve t 90 is adapted for revolution by hand, using the collar m as a screw box to bodily slide the tube i a distance quite independent of any operation of the weight x , which has the effect of inclining the axis of the pulley g , 95 the jointing of the tubes at h^4 i^4 to the brackets g^2 g^3 being necessary when this part of the invention is used. After setting the inclination of the axis of the pulley g the operation of the weight x causes all the collars j , m , u , and v to move as one piece with the tubes h and i , which always move parallel and together.

100 It is a constructional feature to arrange the axes of the tubes h and i in the same plane as the axes of both pulleys f and g .

A swinging catch w is carried by the sliding tube i , and is adapted for engagement with a stud w^2 fixed to the machine's frame, 105 for the purpose of holding the pulleys f and 110

g in their closest positions to each other, against the action of the weight, when putting on or taking off a band *d*.

From a socket 2 integral with the base of the machine's frame is supported a saddle 3 capable of being set either horizontally or at an angle. Said saddle is pivoted at 4 to its support and is adapted to be clamped at 5 within the limits of the quadrant 6. Upon 10 this saddle is mounted a middle slide 7 adapted to be moved by the hand lever 8 to advance said slide to and from the band *d* and table *c*. Upon this middle slide is mounted a top slide 9 to form a rest surface 15 for work or a carrier for work. This top slide can be moved by any suitable mechanical devices truly in a direction at right angles to the movement of the middle slide 7, namely, across the running band *d*. If the 20 saddle 3 is tipped at an angle the work surface of the top slide 9 is also tipped to the same angle.

The elevated part *a*² is provided at 10 10 with lateral projections to which complementary projections *c*² *c*² of the table are rigidly clamped by the pins 11 11. The pieces 10 10 are formed with slots 12 within which the pins 11 may be adjusted. By these devices the table *c* may be laterally adjusted 30 on the machine's frame to enable either of its longitudinal edges 13 13' to be set to the adjacent edge of the endless band *d*.

Having now described my invention what I claim and desire to secure by Letters 35 Patent is:—

1. In an endless band grinding and polishing machine, the combination of two end pulleys over which the band runs, a table arranged between the two pulleys and over 40 which one stretch of the band travels, a pair of rods carrying one of said pulleys, one at each end of said pulley and arranged, respectively, adjacent the longitudinal edges of said table and mounted for movement in 45 a straight line longitudinally of said table, and a weight automatically operating on said rods to normally separate the two pulleys for tensioning the band and maintaining same, substantially as described.
- 50 2. In an endless band grinding and polishing machine, the combination of two end pulleys over which the band runs, a table ar-

ranged between the two pulleys and over which one stretch of the band travels, means carrying one of said pulleys and arranged to 55 slide in a straight line longitudinally of the table, a transverse rocking shaft, means connecting said rocking shaft to said slideable means to impart movement to the latter when said shaft is rocked, and a weight 60 tending to rock said shaft to automatically separate the two pulleys for tensioning the band and maintaining same, substantially as described.

3. In an endless band grinding and polishing machine, the combination of two end pulleys over which the band runs, a table arranged between the two pulleys and over which one stretch of the band travels, a pair of rods carrying the movable pulley, one 70 mounted adjacent to each longitudinal edge of the table, and arranged to slide in a straight line longitudinally of the table, and one of which is lengthwise adjustable to incline the axis of the movable pulley, and a 75 weight automatically operating on said rods to normally separate the two pulleys for tensioning the band and maintaining same, substantially as described.

4. In an endless band grinding and polishing machine, the combination of two end pulleys over which the band runs, a table arranged between the two pulleys and over which one stretch of the band travels, a pair of rods carrying the movable pulley, one adjacent 80 each of the longitudinal edges of the table, and mounted to slide in a straight line longitudinally of the table, one of said rods being provided with a pair of collars, a screw-threaded sleeve revolvably fitted over 90 said rod between said collars, and a weight automatically operating on said rods, in the one case through the sleeve, to normally separate the two pulleys for tensioning the band and maintaining same, substantially as 95 described.

In testimony whereof I have hereunto set my hand in presence of two subscribing witnesses.

CHARLES RALPH TOWNSEND.
